UNITED STATES PATENT OFFICE.

PETER EDUARD GELDHOF, OF SYRACUSE, NEW YORK, ASSIGNOR, BY MESNE ASSIGNMENTS, TO UNITED STATES HOFFMAN MACHINERY CORPORATION, OF NEW YORK, N. Y., A CORPORATION OF DELAWARE.

STEAM-SPRAYING AND STEAM-HEATED MEMBER FOR GARMENT-PRESSING MACHINERY.

Application filed November 28, 1921. Serial No. 518,407.

To all whom it may concern:

- Be it known that I, PETER EDUARD GELDHOF, a citizen of the United States, residing at Syracuse, in the county of Onondaga and 5 State of New York, have invented certain new and useful Improvements in Steam-Spraying and Steam-Heated Members for Garment-Pressing Machinery, of which the following is a specification.
- 10 This invention relates to garment pressing machinery, and especially to improvements in the construction of the pressing members or parts of the machine which apply steam and pressure to the garment. 15 More particularly it relates to improved steam spraying and steam heated pressing members for garment pressing machinery. It is a primary object of this invention to improve the structure of the head and buck 20 of garment pressing machines to the end that this part shall be relatively small in structure, light in weight, simple to manufacture, and capable of ejecting or spraying steam which has a relatively small moisture 25 content. And an additional object is to produce a pressing member adapted to contain a quantity of steam for heating the working face of the member and for steam spraying the garment, the said steam being 30 first used to heat the member and thereafter to steam spray the garment.
- In order to disclose the principles of my invention and show the same in one practical form, I attach hereto a drawing, and 35 though there is shown a preferred form of construction, I claim a right of protection as to all such changes as may come within the scope of my invention.
- In the drawings, Figure 1 shows a front 40 view of a pressing member carried by the press lever of a steam garment press; and the frame of the machine and other features not relating to this particular invention are broken away; and the lower pressing member, the buck, is not shown. Figure 2 shows 45 a cross sectional view of the pressing member as developed along the line 2—2 of Figure 1. Figure 3 shows a longitudinal sectional view of one end of the head.
- 50 A pressing member, such as a head, buck, or work support, for use on steam garment pressing machines, built in accordance with
- the plans of this invention, comprises a member, usually a cast body, having a relatively flat imperforate pressing face, or curved if desired, with an arched wall formed over the pressing face to form a hollow heating chamber which contains steam to heat the pressing face and steam to treat the garment. Within this heating chamber 55 there is provided a spray chamber having a foraminous face, and this spray chamber does not contain steam except during the interval when the garment is receiving steam treatment. The steam in the heating chamber serves to maintain the walls of the spray chamber passage at a high temperature, and to keep the spray chamber as hot as the heating chamber in order that condensation 60 will not take place when steam is flowing thru the spray chamber upon the garment.
- It is a primary object of this invention to improve the structure of the head and buck 65 of garment pressing machines to the end that this part shall be relatively small in structure, light in weight, simple to manufacture, and capable of ejecting or spraying steam which has a relatively small moisture 70 content. And an additional object is to produce a pressing member adapted to contain a quantity of steam for heating the working face of the member and for steam spraying the garment, the said steam being first used to heat the member and thereafter to steam spray the garment.
- For the purpose of describing this invention, there is shown a pressing head, or the upper pressing member of a steam garment 75 pressing machine; but it of course is understood that a buck, or the lower pressing member, or the work support, may similarly be constructed in accordance with the plans of this invention. The pressing head comprises a pressing surface wall 5, which wall 80 may either be flat or curved dependent upon the particular style and design of pressing to be executed. A heating chamber H is formed by the wall 6; and the wall 6 has a boss 7 to receive a steam spraying valve 85 as later described. The walls 5 and 6 of the pressing head may be constructed or cast integral if desired; or in some cases it is found more practical to construct the head in two parts, and thereafter join the parts 90 5 and 6 together by screws or other suitable means. A steam supply pipe 8 connects with the heating chamber H to supply steam to the head, and another pipe, not shown, may be similarly employed to provide an outlet for the steam in order that a steam circulation is produced in the head. A drain pipe, not shown herein, is usually employed to carry away water of condensation which forms in the head. These parts 95 are not necessarily shown here inasmuch as they constitute known principles and structure in the art.
- A steam spray passage or chamber S is

made on or in the pressing surface wall by providing a wall 10 which is joined to the back surface of the wall 5 so as to form a space S which is preferably disposed centrally of and extends longitudinally substantially from end to end of the pressing member; and this passage is made relatively small in volume and size. Perforations 11 are made through the pressing wall 5 and 5 connect with the steam spray passage S. This construction leaves imperforate the larger portion of the surface area of the pressing face 5; and produces a foraminous pressing surface along the central portion of 10 the press head.

A press cloth 12 is secured over the working surface of the pressing wall 5 so as to thoroughly distribute the steam to the garment being pressed, and so as to prevent the 20 metal face of the head from contacting the garment. The press cloth 12 is secured to the head by any appropriate means and tightly stretched across the pressing surface. Once the cloth has been used, it becomes soft 25 and pliable so that it flexes outwardly from the wall 5 under the pressure of steam so as to allow the steam to freely traverse the entire length and breadth of the pressing surface; and the steam accumulates in sufficient 30 quantity behind the press cloth as to thoroughly impregnate the parts of the garment being pressed when the head goes forcibly downward onto the garment. The cloth 12 is itself foraminous and steam very readily 35 emits through the entire area of this press cloth onto the garment being treated.

A valve casing 15 is disposed through the boss 7 and is joined with the wall 10. This 40 valve casing is provided with a number of holes 16 so as to admit steam from the heating chamber H into the valve casing. Suitable locking and jam nuts 17 serve to securely anchor the valve casing 15 in position and to form a steam tight joint between this part 45 and the boss 7; and in addition to these parts, a handle support bracket 18 pivotally carries a valve handle 19. A valve stem 20 is confined in the valve casing 15, and the lower end of this stem rests against a valve 50 seat made in a bushing 22. A compression spring 21 is disposed between a shoulder or pin integral with the stem in the handle 19 so as to cause the valve stem to positively seat in the bushing 22. The valve assembly is 55 usually made up in the form of a complete unit by assembling the several parts within and upon the valve casing 15; and thereafter the complete unit is mounted in the head.

60 It is to be noted how the steam confined in the heating chamber H lies in contact with the wall 10 of the spray passage S; and this wall 10 is designed to transmit heat from the steam in contact therewith through 65 and into the passage S so as to maintain the

spray passage in a relatively hot condition. The spray passage S is maintained at a temperature substantially equal to the temperature of the chamber H, and therefore when steam flows from the chamber H into the 70 passage S, there results little or no condensation due to this movement of steam from one chamber to another. This construction therefore has the advantage of providing a relatively small spray chamber passage part- 75 ly surrounded by steam contained in the heating chamber, and with the additional advantage that the size and thickness of the head is held to small limits.

In Figure 1 the head is shown as carried 80 by a press lever 25, which lever pivots on a fulcrum pin or shaft 26 fixed in brackets 27, the brackets being broken away from the frame of the machine not shown. In operation, the press lever 25 raises and lowers the 85 head to execute the pressing operation as is understood by those conversant with the art.

When the operator working the garment press actuates the handle 19, causing the 90 valve 20 to lift from the bushing seat 22, steam under pressure rapidly flows from the valve casing 15 and through the entire length of the spray passage S and continues 95 downwardly through the foraminated wall 5 and is then distributed over the entire area of the wall by the press cloth 12. As the steam accumulates behind the press cloth, it discharges through the cloth onto the garment to sterilize the garment, raise the nap thereof by steam expansion, and produces a 100 general renewed appearance.

Claims:

1. In an improved pressing element for use in garment pressing machines, the combination of a pressing element having a relatively large hollow chamber located upon one face thereof; means for admitting a heating medium into said chamber; a second chamber formed within the first chamber; the pressing member having that wall 105 which is adjacent said smaller chamber perforated, and the upper portion of said smaller chamber being provided with a threaded opening which is in alignment with the opening formed in the corresponding wall of the larger chamber; a valve casing adapted to be passed through the opening in the wall of the outer chamber, the lower end of the valve casing being threaded and adapted to be screwed into the opening 110 formed in the smaller chamber; a valve seat mounted in the lower end of said valve casing; a valve stem mounted in the casing and extending downwardly therefrom; and means for guiding said valve stem, the valve 115 casing being provided with openings to admit the heating medium from the larger to the smaller chamber when the valve stem is unseated from the seat.

2. In an improved pressing element for 120

garment pressing machines, the combination of a metallic head; a relatively large chamber formed upon one face thereof, said chamber being provided with an upwardly extending boss having an opening in the upper end thereof; a second chamber formed within the first chamber and having its walls, other than the outermost one, spaced from the walls of the large chamber the outermost wall forming a continuation of the pressing face of the pressing member, said outermost wall being perforated in line with the smaller chamber, and said smaller chamber being provided with a threaded opening standing in alinement with the opening in the boss; a valve casing extending inwardly through the opening in the boss, the lower end of said casing being threaded and adapted to be screwed into the opening formed in the upper portion of the smaller chamber; a valve seat secured in the lower end of said casing; a valve stem mounted for reciprocation in the casing, said stem extending outwardly beyond the outer end of the casing; means for normally moving the valve stem inwardly to close the entrance to said smaller chamber; and means for moving the stem in the opposite direction, the valve casing being provided with openings affording communication between the interior thereof and the larger chamber.

In testimony whereof I have hereunto affixed my hand and seal this 14 day of November, 1921, in the city of Syracuse, county of Onondaga, State of New York.

PETER EDUARD GELDHOF. [L. S.]
